THOMAS E. LUTNER, OF PHILADELPHIA, PENNSYLVANIA.

Letters Patent No. 90,455, dated May 25, 1869.

IMPROVED CRANK-AXLE FOR WAGONS.

The Schedule referred to in these Letters Patent and making part of the same.

To all whom it may concern:

Be it known that I, THOMAS E. LUTNER, of Philadelphia, in the county of Philadelphia, and State of Pennsylvania, have invented a new and improved Crank-Axle for Wagons; and I do hereby declare that the following is a full, clear, and exact description thereof, which will enable others skilled in the art to make and use the same, reference being had to the accompanying drawings, forming part of this specification.

This invention relates to improvements in cranked axles for wagons, trucks, &c., whereby it is designed to provide such a construction of the same as will admit of more room between the vertical portions of the axle, without increasing the distance between the wheels, than is afforded by the present construction, as will be more fully described on reference to the accompanying drawings, wherein—

Figure 1 represents a side elevation of my improved axle, and

Figure 2 represents a section of the same.

Similar letters of reference indicate like parts.

It is desirable to provide the greatest breadth for the load that may be within the limits of the total breadth of the wagon or truck, especially where it is desirable to set the wheels, so as to run on the rails of street-railroads, which are commonly slightly narrower than the wheels of trucks are desired to be.

And in the case of the employment of cranked-axle trucks, having the wheels within the limit of the breadth of the said rails, it is exceedingly difficult to make

them wide enough for conveniently loading some kinds of hogsheads, such as sugar or tobacco-hogsheads, without reducing the length of the hubs to such an extent as to weaken them.

To meet these difficulties, I propose to reduce the breadth of the vertical portions *a* of the axles, and correspondingly increase it transversely, as represented at *b*, in fig. 2, whereby the distance *c* between the said vertical parts may be correspondingly increased, the said reduction being made on the outer sides of the vertical parts *a*, and curved, as represented at *d*, allowing the hubs, which may be correspondingly curved, to work closely up to the said reduced and curved portion.

In axles for strong trucks, this arrangement permits an increase of space for the load of from two to five inches, without lessening the length of the hubs.

Having thus described my invention,

I claim as new, and desire to secure by Letters Patent—

Cranked axles for wagons, having the vertical portions *a* thereof reduced in the direction of the length of the axle, and widened correspondingly in the direction transversely to the said vertical parts, substantially as and for the purpose described.

THOS. E. LUTNER.
